UNITED STATES PATENT OFFICE.

JAMES N. MCCOY, VINCENNES, INDIANA.

COOLING MEDIUM FOR INTERNAL-COMBUSTION ENGINES.

1,102,777.

Specification of Letters Patent.

Patented July 7, 1914.

No Drawing.

Application filed January 26, 1912. Serial No. 673,534.

To all whom it may concern:

Be it known that I, JAMES N. McCoy, a citizen of the United States, residing at Vincennes, in the county of Knox and State 5 of Indiana, have invented a new and useful Cooling Medium for Internal-Combustion Engines, of which the following is a specification.

This invention relates to liquid composition for use in circulatory systems as means for cooling or preventing excessively high temperatures in vessels or high speed machinery, the invention having reference more particularly to means for cooling the 15 cylinders of explosion engines, especially those of automobiles.

Heretofore it has been the practice to cool explosion engine cylinders by means of circulating water, and the water has been permitted to remain in the circulatory system 20 when the engines have not been used in the winter seasons with the result that the water has frozen and caused considerable expense for repairs due to bursting of pipes or 25 radiator coils, and it is the object of the present invention to provide cooling medium for the cylinders that may be safely used throughout the winter seasons without risk 30 of entailing disastrous results on account of freezing of the cooling liquid at any low atmospheric temperature to which the liquid is subjected in practical use, a further object being to provide a safety engine cooler that will be adapted for northern as well as 35 southern latitudes and obviate the necessity of drawing off the circulatory water hitherto found necessary in order to prevent damage due to freezing of the liquid when the automobiles are temporarily withdrawn 40 from service or at night time in cold garages.

A still further object is to provide a safety circulatory composition for cooling explosion engine cylinders that shall not be 45 deleterious to the materials used in the construction of the circulatory system of automobile engines.

A specific object of the invention is to provide a cooling medium for explosion engines that shall have the properties of being 50 low in degree of expansibility and contractibility, in order that the circulatory system of the engine shall not overflow at relatively high temperature nor become 55 deficient in liquid at relatively lower temperatures in action, a liquid having less expansion-

sibility and contractibility than water being desirable for the purpose.

With the above mentioned and minor objects in view, the invention consists in a 60 safety explosion engine cooler comprising a substantially non-freezable cooling liquid for the circulatory system of explosive engines characterized by its ability to remain in a liquid state in a temperature of approximately 25 degrees below zero, Fah.

The invention consists more specifically in a new and useful composition of matter for cooling engine cylinders, and in the combinations of elements hereinafter particularly described and defined in the accompanying claim.

The engine cylinder water jackets, the radiator coil and the several conduits connected with them and a circulatory pump 75 constitute the circulatory system of an explosion engine, as will be understood, and in some cases the circulatory pump may be omitted from the system. The improved cooling composition fills the circulatory 80 system and, as will be understood, circulates through the system, the composition becoming heated in the water jackets and then cooled in the radiator and returns to the water jacket to cool the cylinders and carry 85 away the heat therefrom, the process being continuous, as will be understood.

The liquid medium for the circulatory system is a composition which preferably consists, stated in non-technical terms, of 90 water and sodium thiosulfate, and in some cases potassium permanganate; or, the liquid may be composed of other equivalent liquid substance capable of withstanding 95 the lowest degree of temperature, in which the use of automobiles is practicable or desirable, without freezing in the circulatory system for cooling the explosion cylinders.

The composition of matter constituting 100 the cooling liquid preferably employed consists of sodium thiosulfate in the proportion of sixty-four ounces dissolved in distilled water of sufficient quantity to make one gallon of the composition, and preferably one-half ounce of potassium permanganate included in the gallon quantity. In order to obtain a stable solution, the sodium thiosulfate is dissolved in four parts of cold distilled water. The mixture, including the potassium permanganate if desired, is boiled 105 fifteen minutes and then filtered. A sufficient quantity of the composition is

poured into the circulatory system of the engine to completely fill it. A sufficient quantity of water is added as required to compensate for evaporation of the composition in use. The composition is permanent and ordinarily need not be renewed.

The composition formed of water and sodium thiosulfate is proven in practice to have the qualifications requisite to resist the tendency to freeze under the conditions commonly imposed on automobile engines, in the most severe winter atmosphere in habitable latitudes, and is not more deleterious than water alone to the metals with which it comes in contact, and the slight tendency of the composition to cause or to permit oxidation of the metals, is obviated when the potassium permanganate is included as one of the ingredients of the composition, the latter chemical acting as a preservative agent because of the affinity between iron and manganese, in consequence of which a coating is deposited upon the walls of the engine cylinders and circulatory ducts which, thus protected, do not so readily yield to oxidation. Without the potassium permanganate being present in the composition, however, there is no tendency on the part of the sodium thiosulfate to corrode metals, but water being known to have such tendency it is desirable to counteract it in the improved composition.

The improved composition gages a specific gravity of 1.027 by Baumé hydrometer

test, is not changed in character by the heat of the engine cylinders, and circulates freely either in pump or thermo-siphon systems; it has less expansion under heat, or is slower in expanding and contracting than a like quantity, by volume, of water.

In practical use, the improved engine cooler is caused to act in the manner required as a result of the design of the circulatory system, the liquid cooling medium circulating in the system and absorbing the heat from the cylinders and giving it off in the radiator as is customary. When the engine is not in use the liquid remains in the circulatory system without endangering the system in freezing temperatures, so that the cooling composition is always in proper condition for use when required.

Having thus described the invention, what is claimed as new is:—

A composition of matter for cooling explosion engine cylinders, said composition consisting of the liquid formed by the combination of water, sodium thiosulfate and potassium permanganate, the composition being capable of withstanding inordinately low degrees of cold without freezing.

In testimony whereof, I affix my signature in presence of two witnesses.

JAMES N. McCOY.
